UNITED STATES PATENT OFFICE.

ALFRED H. S. SWAN, OF ROCHESTER, NEW YORK, ASSIGNOR TO ROCHESTER STAMPING COMPANY, OF ROCHESTER, NEW YORK, A CORPORATION OF NEW YORK.

LAMP-BRACKET.

1,088,848.

Specification of Letters Patent.

Patented Mar. 3, 1914.

Application filed October 30, 1911. Serial No. 657,581.

To all whom it may concern:

Be it known that I, ALFRED H. S. SWAN, of Rochester, in the county of Monroe and State of New York, have invented certain new and useful Improvements in Lamp-Brackets; and I do hereby declare the following to be a full, clear, and exact description of the same, reference being had to the accompanying drawings, forming a part of 5 the specification, and to the reference-numerals marked thereon.

My present invention relates to stoves and more particularly to the small vapor or fluid burning heating units as typified by chafing 15 dishes and tea stands, and it has for its object to so mount the lamps or burners of these devices that they present their flames very close to the surface to be heated when in operative position, yet may be readily 20 moved to a position in which they will become easily accessible for filling, adjusting or other manipulations.

To these and other ends the invention consists in certain improvements and combinations of parts all as will be hereinafter 25 more fully described, the novel features being pointed out in the claims at the end of the specification.

In the drawings: Figure 1 is a side elevation of a tea stand constructed in accordance with and illustrating one embodiment of my invention; Fig. 2 is a horizontal section taken substantially on the line 2—2 of Fig. 1 and giving a plan view of the lamp and its 30 support; Fig. 3 is a detail elevation of the bearing of the bracket arm taken in partial section substantially on the line 3—3 of Fig. 2 and Fig. 4 is a detail cross section through the table, showing the lamp body about to 35 rise into position thereon.

Similar reference numerals throughout the several figures indicate the similar parts.

As before indicated I have shown my improvements applied, in the present instance, 40 to a tea stand or stove embodying a top 1 and two oppositely arranged supporting legs 3, between the lower portions of which extends a table 4 for the lamp. The top 1 may be continuous or open or the kettle or 45 other vessel may be so supported that a top, such as shown, is not altogether necessary, but it is herein illustrated to represent approximately the surface against which the flame is to be directed.

50 The lamp 5 may be of any suitable type desired, that shown being a vapor lamp hav-

ing a burner 6 and a controlling knob 7. Its operative position is on the table 4 and it has hitherto been customary to hold it in place by providing a socket on the table into which 50 it is lowered. But the objection to this construction has been that in order to provide room for inserting the lamp between the edge of the socket and the surface to be heated before it is dropped in place, the 55 height of the stand must be unduly increased and in dropping the lamp into the socket its burner and hence its flame is removed just that much farther from the surface to be heated and therefore rendered less effective. 60 Furthermore, the operator must reach in beneath the standard to manipulate the lamp. To obviate these objections I provide a swinging bracket for the lamp which comprises in the present instance, an elbow- 65 shaped arm 8 preferably composed of a single piece of wire having its inner end bent downwardly at 9 and removably supported in a suitable bearing 10 secured to the inner side of one of the legs 3, while the outer end 70 of the arm is preferably rigidly attached to a ring 11 into which the lamp body 5 fits. The latter has a flange 12 at its upper edge that prevents it from dropping through the ring and when it is desired to fill the lamp or 75 adjust it or manipulate it in any way, it is swung outwardly on the bracket from the position of Fig. 1 to that indicated in dotted lines in Fig. 2. The peculiar bent shape of the arm 8 allows considerable radius to this 80 movement so that the ring 11 of the bracket and the lamp are supported at a readily accessible point on the outside of the leg 3, while when the bracket and lamp are swung 85 inwardly again beneath the stove top, the intermediate portion of the arm 8 engages the 90 inside of the leg as a stop, as shown in Fig. 2, to define the operative position of the lamp, so far as its inward movement is concerned. Were the lamp merely supported 95 in this swinging manner when in operative position, however, the slightest movement might cause it to swing from beneath the stove top either partially or wholly, and to prevent this I make arrangements whereby 100 the lamp actually rests upon the table 4 when in its operative position. To this end it is loosely fitted in the bracket ring 11 so that it is allowed slight vertical movement and its flange 12 does not, therefore, engage 105 the ring when in the position of Fig. 1, and the frictional engagement of the lamp bot-

tom with the table is sufficient to hold it in place, although the ring of course still holds it erect against tilting. When it is pushed off from the table, however, it is supported solely by the bracket and the ring and when swung back it rises slightly onto the table to produce which movement its lower edge is beveled or provided with a cam surface 13 that coöperates with the edge of the table to 10 raise the lamp in the bracket ring.

I claim as my invention:

1. The combination with a stove top and a supporting leg therefor, of a lamp and a bracket for carrying the same embodying 15 an elbow shaped arm pivoted on the inside of the leg and permitting the lamp to be swung outwardly from beneath the stove top, the intermediate portion of the arm engaging the inside of the leg as a stop when 20 the lamp is swung back to define the position of the latter beneath the stove top.
2. The combination with a support embodying a stove top and a table beneath the same, of a laterally pivoted lamp bracket 25 embodying a lamp supporting ring adapted to swing from beneath the stove top and above the table and a lamp supported in and resting on the bracket ring with its bottom below the level of the table and having vertical movement relatively to the ring 30 permitting it to rest upon the table independently of the support of the bracket ring when the latter is beneath the stove top.
3. The combination with a support em-

bodying a stove top and a table beneath the same, of a lamp supported on the table and a laterally pivoted lamp bracket connected to the lamp to swing it from beneath the stove top and to support it when off the table with its bottom below the level of the latter, the lamp being permitted vertical movement relatively to the table and said parts being provided with means for elevating the lamp onto the table when returned comprising a cam surface on one of 45 them engaged by the other.

4. The combination with a stove top having oppositely arranged supporting legs and a table extending between the legs below the top, of a bracket comprising an elbow shaped arm pivoted on the inside of one leg and carrying a supporting ring adapted to assume a position beneath the stove top or to swing laterally to the opposite side of the leg and a lamp carried 50 loosely within the ring to rest on the table in one position of the bracket and to be supported wholly by the latter in its other position, the elbow of the bracket being proportioned to engage the leg by which it is carried to define the position of the lamp on the table and to straddle said leg when the bracket is so swung as to dispose the lamp 55 on the other side of the leg.

ALFRED H. S. SWAN.
